[57] CLAIM

The ornamental design for a seat, as shown and described.

DESCRIPTION

FIG. 1 is a front perspective view of a seat showing my design in the form of a vehicle seat;

FIG. 2 is a front elevational view of the seat design of FIG. 1; and

FIG. 3 is a rear perspective view of a seat showing a second embodiment of my design in the form of a household chair or similar article;

The undisclosed bottom of the seat is conventional in appearance.

FIG.1

FIG.2

FIG. 3
